DESIGN FOR A CURTAIN OR THE LIKE

Charles A. Hanington, Freeport, N. Y.

Application December 1, 1944, Serial No. 116,652

Term of patent 3½ years

(Cl. D47—6)

To all whom it may concern:

Be it known that I, Charles A. Hanington, a citizen of the United States, residing at Freeport, in the county of Nassau and State of New York, have invented a new, original, and ornamental Design for a Curtain or the like, of which the following is a specification, reference being had to the accompanying drawing, forming a part thereof.

The figure in the drawing is a plan view of a curtain showing my new design.

I claim:

The ornamental design for a curtain or the like, as shown.

CHARLES A. HANINGTON.
